CLAIM

The ornamental design for a milker unit short milk tube milk claw end connector, as shown and described.

DESCRIPTION

FIG. 1 is a perspective view of a milker unit short milk tube milk claw end connector showing the design;

FIG. 2 is an isolated perspective view thereof;

FIG. 3 is a front elevational view thereof and is a mirror image of the rear elevational view thereof;

FIG. 4 is a right side elevational view thereof, and is a mirror image of the left side elevational view thereof; and,

FIG. 5 is a bottom end view thereof.

A teat cup liner and the short milk tube are shown in broken lines for illustrative purposes only, and form no part of the claimed design.
